DISPLAY RACK

Leonard J. Kehlhoff, Merrill, Wis.

Application August 28, 1934, Serial No. 741,845

3 Claims. (Cl. 211—154)

This invention relates to display racks particularly designed to display shirts, nightgowns, pyjamas, and other articles of wearing apparel, these articles being packed flat, the object of the 5 invention being to provide a rack which will permit the articles to be displayed in an upright position and permit each article to be disposed slightly above the article in advance thereof so that the color and size of the shirt or other article may be 10 seen at a glance.

A further object is to provide a rack of this character which will permit any article or articles to be withdrawn therefrom without disturbing the general display.

15 Another object is to provide a rack of this character which is built up of units that may be readily extended to secure any size display desired, and a further object is to provide a rack which is very simply constructed, which may be readily assembled, which is light and portable, and which is adapted to hold display cards, price cards, or the like.

My invention is illustrated in the accompanying drawings, wherein

25 Figure 1 is a front elevation of my improved rack with shirts carried thereby;

Fig. 2 is a perspective view of the rack, the shirts being removed;

30 Figs. 3 and 4 are fragmentary edge elevations of two of the joints between the sections of the rack, and

Fig. 5 is a fragmentary elevation of the joint between the side members of the rack and the base, the cross bar of the base being in section.

35 Referring to the drawings, and particularly Fig. 2, it will be seen that I have provided a base for the rack, this base comprising a plurality of transverse bars 10, each bar at its ends being formed with a downwardly extending foot 11, the foot 40 being turned inward and then upwardly extended. The feet of the cross bars 10 are connected together by longitudinally extending bars 12 constituting braces, and riveted, bolted, or otherwise secured to the downwardly extending feet 11 by 45 means of screws, bolts, or like devices 13. The shirt supporting means for the rack comprises two side members formed of consecutive sections. In Fig. 2 there are six sections shown, each section being formed of a strip of metal 14 bent to 50 provide a series of steps 15. At the forward end of each step the strip of metal 14 is extended upward, as at 16, to form a guard lug.

The upper end of each strip 14 is horizontally extended, at 17, so as to fit beneath the last step 55 of the next adjacent section and be bolted there-

to by the bolts 18, it being understood, however, that rivets or other fastening devices might be used in place of the bolts. The forward end of each strip 14 is upwardly extended to form vertical bars 19, which bars extend upward to any desired height, as shown in Fig. 2, the upper ends of the bars of opposite sections being connected by a transverse cross bar 20, which is riveted or bolted to the vertical bars 19. These bars 19 with the cross bars 20 constitute separator frames, between which a plurality of shirts or other articles are to be disposed, and whereby these shirts or other articles will be supported in an approximately vertical position. These bars 19 may be formed of thin sheet metal with a reinforcing rib, but of course I do not wish to be limited to this.

The series of sections constituting the side members of the rack are bolted to each other by the bolts 18 heretofore described, and at intervals are supported by upwardly extending legs 22 whose lower ends are flanged, at 23, and bolted to the ends of the cross bars 10 of the base. The upper end of each leg or supporting member 22 is angularly bent, at 24, and the bolt 18 passes through this angularly bent portion 24, as shown in Fig. 3. Preferably the separator frames of the parts 19 and 20 will be spaced equidistantly from each other and will permit the insertion of a plurality of shirts or other articles between each pair of separator frames. I have shown these frames separated by three steps so that three articles may rest upon these steps and be supported thereby in upwardly stepped relation. These separator frames hold the articles 30 in an approximately vertical position and permit any one article to be withdrawn without disturbing the general effect of the display. Preferably the forwardmost separator frame will have clips 25 applied to the cross bar 20 thereof, so that a display card, price list, or other advertising matter, may be supported upon this front separator frame. Preferably the last separator frame of the series is braced from the last cross bar 10 of the series by means of an upwardly and forwardly extending brace, designated 26, which is twisted 35 in its length so as to make it particularly resist rearward deflection, the lower end of the brace 26 being angularly bent and bolted to the rear cross bar 10 by means of the bolt 27. The upper end of this brace is bolted to the uppermost cross bar 40 20, by a bolt or screw 28.

For the purpose of bracing the side frames from each other, a plurality of cross bars 29 are provided connected at intervals to the side members and bolted at their ends to the upper ends 55

of the legs 22. Preferably, as shown in Figs. 2 and 3, these cross bars 29 are disposed between the flange 24 of the corresponding leg 22, and the lowermost step 15 of a section, and the bolt 18 passes through the lowermost step of the section through the cross bar 29 and through the flange 24.

While in certain of the sections the strip 14 may be extended integrally upward to form the vertical separator bars 19, yet under some circumstances these separator bars may be formed separate from the strips 14, as shown in Fig. 3, the separator bar 19 being angularly bent at its lower end, at 30, to rest upon the step 15 and be held thereto by the bolt 18. The rearmost separator bars 19 are formed in this manner, as shown in Fig. 2, tho I do not wish to be limited to this. In Fig. 5 the separator bar 19 is illustrated as being integral with and as forming a continuation of the strip 14.

While I do not wish to be limited to this, I can apply to the uppermost cross bar 29 a vertically extending supporting bar 31 which at its lower end is riveted or bolted to the bar 29, and at its upper end is riveted, bolted, or otherwise attached to the uppermost cross bar 20 by means of the screw or bolt 28, and attached to the upper end of this vertical bar 31 is a member 32 supporting a cross piece 33 having vertical standards 34 and spring clips 35 overlying these standards, this arrangement permitting a show-card, price card, or other advertising display material to be disposed within these clips and supported above the articles carried by the rack.

It will be seen that I have provided a rack which is very light and very simply constructed, which may be readily assembled or disassembled, and which may be made of any desired size by combining several units. It will also be seen that I have provided a rack which will support a series of like articles in step formation so that each and every article may be seen, its color observed, and the size marks of the article readily noted, and that these articles are supported in spaced relation to each other so that any one or more of the articles may be removed from the rack without disarranging or disturbing any other article on the rack and without affecting the general display. It will likewise be seen that this construction permits other articles to be inserted when articles have been removed from the rack, without in any way affecting the general display. The rack is designed with a sufficient rise to cause the articles to project one above the other in succession. The upwardly extending lugs 16 constitute guards or

stops preventing one article from sliding down when an article in front has been removed. The separator frames prevent any article from falling forward or backward and permit any article to be withdrawn without disturbing the display generally. The member 32 at the upper end of the support 31 is adjustable vertically so that it may be used as a back-rest for longer folded articles or for a display clamp as heretofore stated.

While I have described these parts as being connected to each other by bolts, screws, or rivets, it will be understood, of course, that the various sections may be spotwelded to each other.

What is claimed, is:

1. A display rack including a base having transverse elements and feet at the ends of the transverse elements, upwardly and rearwardly extending side members disposed above the base and formed to provide a series of steps, the side members being connected at intervals by cross bars, legs extending upward from the base and supporting the said members at intervals, braces connecting the side members with each other, and separator frames carried by the side members at spaced intervals and extending upwardly therefrom, each frame comprising laterally disposed vertical bars and a top cross bar.

2. A display rack including a base, side members carried by the base and formed of a series of sections, the side members extending upwardly and rearward and each section being formed to provide a plurality of steps separated from each other by upwardly extending lugs, means extending upward from the base at intervals and engaging beneath the side members and bolted thereto, cross bars connecting the side members and bolted thereto, and separator frames carried by the side members and extending upward therefrom at spaced intervals.

3. A display rack including a base, side members carried by the base and formed of a series of sections, the side members extending upwardly and rearward and each section being formed to provide a plurality of steps separated from each other by upwardly extending lugs, means extending upward from the base at intervals and engaging beneath the side members and bolted thereto, cross bars connecting the side members and bolted thereto, and separator frames carried by the side members and extending upward therefrom at spaced intervals, certain of the separator frames being integral with the sections of the side members, and certain of the separator frames being bolted to the side members.

LEONARD J. KOHLHOFF. 55
